UNITED STATES PATENT OFFICE.

CHARLES S. NELSON, OF SANDPOINT, IDAHO, ASSIGNEE TO MALVERN L. BRUCE, OF SANDPOINT, IDAHO.

PUNCTURING WHEEL.

Application filed June 12, 1926. Serial No. 115,652.

My present invention relates to improvements in puncturing wheels of the type used in connection with machines for puncturing or piercing telegraph and telephone poles, logs, piles and other similar objects preparatory to treating the wood to a preservative coating or bath to prevent decay of the wood. A predetermined portion of the exterior area or surface of the timber is punctured to an approximate depth of one-half to three-quarters of an inch, and the wheel or roller of my invention is adapted to be rotated, while retained in stationary position, by the movement of the work, or the work may be retained in stationary position and the wheel caused to travel over its surface in the performance of its function.

The wheel or roller carries one or more annular series of spikes or puncturing tools adapted successively to be forced to penetrate the surface of the work, and means are provided whereby the spikes are positively retained in a tangential position with the relation to the axis of the wheel when penetrating the wood surface to insure proper entry of the spike. Resilient means are provided for the spikes whereby they may adapt themselves for proper withdrawal from the wood to prevent breaking or tearing of the wood fiber or grain. By the special arrangement of the spikes to the wheel a clean and smooth puncture is provided in the wood without unnecessary or material weakening of the wood structure.

The invention consists in certain novel combinations and arrangements of parts involving the wheel and spikes as will herein-after be more fully pointed out and claimed.

In the accompanying drawings I have illustrated one complete example of the physical embodiment of my invention wherein the parts are combined and arranged according to the best mode I have thus far devised for the practical application of the principles of my invention.

Figure 1 is a view in side elevation of the puncturing wheel showing its relation to a portion of a pole or post to be punctured.

Figure 2 is a transverse sectional view of the wheel at line 2-2 of Figure 3.

Figure 3 is a face view of the wheel partly broken away to disclose its interior construction.

Figure 4 is a perspective view of one of the spikes.

Figure 5 is an edge view of a portion of the wheel.

The wheel rotates or revolves in the direction of the arrows in Figure 1 and the spikes carried at the periphery of the wheel successively enter the surface of the wood on the working stroke of the wheel when the wheel travels with relation to the pole P. On its return stroke (to the left in Figure 1) the wheel is elevated to lift the spikes out of contact with the log while the latter is being turned to present a fresh surface for puncturing, as indicated in my co-pending application for patent Ser. No. 70,969, filed November 23, 1925. Sufficient pressure is applied to the wheel to cause the spikes to enter the surface of the wood to the required depth, for forming the spike-hole or puncture.

The wheel is preferably made up of a plurality of intermediate circular disks, as 1 and 2, and complementary circular side plates 3 and 4, the disks and plates being spaced apart to provide openings through the wheel, and joined by transversely extending bolts 5 and nuts 6 thereon, which bolts pass through the side retaining rings 7 at the periphery of the wheel. The intermediate disks are provided with central open hub rings 8 mounted upon a hub sleeve 9, and retaining collars 10 are employed on the hub sleeve to retain the central portion of the sections of the wheel.

The hub sleeve is journaled on a wheel shaft 11 passing through a forked yoke 12 supported at the end of a suspending bar 13 which is carried on a suitable carriage when the wheel travels, or fixed to a stationary support when the work is moved relatively to the wheel.

As here illustrated three annular series of spikes are carried in the spaces of the wheel, but it will be understood that a greater or less number of series may be employed if desired. As shown in Figures 3 and 5 the spikes of the series are staggered, and they project beyond the periphery of the wheel, normally in tangential relation to the axis of the wheel. The spikes are fashioned as indicated in Figure 4 with an intermediate hollow boss 14, a flat, pointed blade 15 to enter the wood with the grain, and a tail-lug 16. They are pivoted on transversely disposed pivot pins 17, carried in the wheel near its periphery, with the spike point exterior

of the wheel and the tail-lug within the wheel. The spike enters the wood while in position tangential to the axis of the wheel and bears against a retaining pin 18 located 5 between the pivot point of the spike and its point or outer edge. A line radiating from the center of the wheel through the point of contact between the sharpened blade or spike 15 and retaining pin 18 will pass outwardly 10 from the wheel through the center of the spike point.

Thus as the spike contacts with the wood as the wheel travels and pressure is applied to the wheel to force the spike into the wood, 15 the pressure is applied through this radial line and the spike is held rigid and positively forced into the wood to make the puncture or hole therein, the tangential position of the spike compensating for the rolling movement of the periphery of the wheel, to insure 20 a clean puncture.

To insure withdrawal of the spike from the wood without breaking or tearing the grain, the spike is permitted to move relatively to the wheel, i. e., to swing on its pivot pin and be withdrawn with an initial radial movement and partial tangential sliding movement from the hole compensated for as the tread line of the wheel travels past the 30 puncture.

For this purpose each spike is provided with a spring 19 located between the spike and the center of the wheel and bearing against the tail-lug of the spike. The springs

are each retained in a space between the 35 wheel sections by pins 20 and 21 near the hub of the wheel and normally urge the spikes against their retaining pins 18 to proper position for entering the wood. After entering the wood the spike is pulled 40 out of its hole by the traveling wheel, and the pin swings on its pivot to radial position for this initial movement against the tension of the spring. Continued rolling movement of the wheel causes the spike to assume 45 a slightly tangential relation to the center of the wheel as its pointed edge is lifted from the hole, but the angle of the pin is not sufficient to cause deformation of the hole or tearing or breaking of the wood fibers. 50

The whole surface of the pole or other object is thus punctured with holes extending inwardly on radial lines toward the center of the pole, for future use as described.

Having thus fully described my invention 55 what I claim as new and desire to secure by Letters Patent is—

A puncturing wheel comprising a plurality of spaced disks and plates, a plurality of annular series of pivoted spikes between said 60 disks and plates, transversely disposed pins for retaining the spikes in rigid position for puncturing, end lugs on the spikes within the wheel, and a spring engaging each lug for permitting relative movement of the 65 spikes after puncturing.

In testimony whereof I affix my signature.
CHARLES S. NELSON.
